DESIGN FOR A SPECTACLE FRONT

Charles O. Cozzens, Southbridge, Mass., assignor to American Optical Company, Southbridge, Mass., a voluntary association of Massachusetts

Application March 24, 1938, Serial No. 76,063

Term of patent 14 years

To all whom it may concern:

Be it known that I, Charles O. Cozzens, a citizen of the United States, residing at Southbridge, in the county of Worcester and State of Massachusetts, have invented a new, original, and ornamental Design for a Spectacle Front, of which the following is a specification, reference being made to the accompanying drawing, forming a part thereof:

Fig. I is a face view of a spectacle front showing my new design;

Fig. II is a plan view of the same.

Fig. III is a sectional view taken on line III—III of Fig. I and looking in the direction of the arrows.

The characteristic features of my design, reside in the provision of a bridge member having an arch or bar-like portion extending between the lenses and a relatively long slender bar-like member having its center portion secured to the

arch of the bridge member along the rear side thereof, and leaving its portions extending from said center portion formed to the contour of the upper edges of the lenses and in the rear thereof.

The bar-like members are shaped and proportioned to blend with each other when in position of use.

The central arch portion of the bridge has a shallow curve when viewed from the top, with the bar, at its point of connection with the central arch portion extending slightly forwardly of the rear surfaces of the portions of the bar shaped to follow the upper edges of the lenses.

The essential features of my design are shown in full lines.

I claim:

The ornamental design for a spectacle front, substantially as shown and described.

CHARLES O. COZZENS.
